UNITED STATES PATENT OFFICE.

JAMES S. KILLEEN, OF DARLINGTON, INDIANA.

RAILROAD-TIE.

No. 835,730.

Specification of Letters Patent.

Patented Nov. 13, 1906.

Application filed May 14, 1906. Serial No. 316,845.

To all whom it may concern:

Be it known that I, JAMES S. KILLEEN, a citizen of the United States, residing at Darlington, in the county of Montgomery, State of Indiana, have invented certain new and useful Improvements in Railroad-Ties; and I do hereby declare the following to be a full, clear, and exact description of the invention, such as will enable others skilled in the art to which it appertains to make and use the same.

This invention relates to railroads, and more particularly to ties therefor, and has for its object to provide a tie which will be cheap though durable, which will be of a plastic type, and which will be arranged for quick attachment of rails thereto.

Other objects and advantages will be apparent from the following description.

20 In the drawings forming a portion of this specification, and in which like numerals of reference indicate similar parts in the several views, Figure 1 is a transverse sectional view of the track, showing the present tie in side elevation. Fig. 2 is a transverse section on line 2 2 of Fig. 1, taken through one of the rail-fasteners. Fig. 3 is a longitudinal section of the tie, taken centrally thereof. Fig. 4 is an end view of the bight.

30 Referring now to the drawings, the present tie comprises a rectangular body portion 5, formed of suitable plastic material and having longitudinal recesses 6 and 7 in its upper and lower faces, respectively, these recesses 35 opening through the ends of the tie. A metallic bar 8 is disposed in the recess 7 and extends beyond the ends of the tie, and a second metallic bar 9 is engaged in the recess 6 and has downwardly-extending end portions 40 10, which lie at the ends of the tie and which are provided with outwardly-extending feet 11 at their lower ends, these feet resting upon the outwardly-projecting end portions of the bar 8, to which they are secured by means of 45 bolts 12.

The bar 9, with its end portions 10, forms what is, in effect, a yoke, the end portions

forming the legs thereof, and the major portion of the bar 9, which is engaged in the recess 6 and which forms the bight of the yoke, 50 is provided adjacent to its ends with longitudinal series of threaded openings 13, which receive the attaching-bolts 15 of rail-fasteners 14, and these fasteners are thus movable to vary the distance between the 55 rails. It will thus be seen that the two bars 8 and 9 substantially brace the body portion 5, and it will be apparent that should the body portion become fractured or otherwise injured to such an extent as to necessitate its 60 removal the bolt 12 may be removed and the body portion easily taken out and another substituted therefor.

What is claimed is—

1. A railroad-tie comprising a body portion having longitudinal recesses in its upper and lower faces, a bar located in the lower recess and extending beyond the ends of the body portion, a bar located in the upper recess and having downwardly-extending end 70 portions at the ends of the body portion, and detachable connections between said downwardly-extending ends and the lower bar, said upper bar being adapted for the attachment of rails thereto. 75

2. A railroad-tie comprising a plastic body portion having longitudinal recesses formed in its upper and lower faces and opening through its ends, a yoke having its bight engaged in the upper recess and lying with its 80 legs at opposite ends of the body portion, said legs having outwardly-extending feet at their outer ends, a bar disposed in the lower recess of the body portion and having end portions engaging the under faces of the feet, 85 said feet and lower bar being detachably connected, and rail-fasteners connected with the upper bar.

In testimony whereof I affix my signature in presence of two witnesses.

JAMES S. KILLEEN.
